UNITED STATES PATENT OFFICE.

OSCAR M. NELSON, OF NEW HAVEN, CONNECTICUT, ASSIGNOR TO THE UNITED STATES SUGAR CO., OF NEW HAVEN, CONNECTICUT, A CORPORATION.

EVAPORATOR.

Application filed October 23, 1919. Serial No. 332,786.

To all whom it may concern:

Be it known that I, OSCAR M. NELSON, a citizen of the United States, residing at New Haven, in the county of New Haven 5 and State of Connecticut, have invented a new and useful Improvement in Evaporators; and I do hereby declare the following, when taken in connection with the accompanying drawings and the characters of 10 reference marked thereon, to be a full, clear, and exact description of the same, and which said drawings constitute part of this application, and represent, in—

Fig. 1 a sectional view of an evaporator 15 constructed in accordance with my invention.

Fig. 2 a top or plan view with the upper part of the body removed.

Fig. 3 a plan view of the drum detached. 20 This invention relates to an improvement in evaporators such as are used to evaporate dense liquors such as cane and beet juices and other liquors requiring concentration, the object of the invention being to provide 25 an evaporator which avoids the necessity of vacuum pumps and sweet water pumps, in other words, to produce a device which will accomplish the desired result of condensing liquors in a simplified manner and the in- 30 vention consists in the construction as hereinafter described and particularly recited in the claim.

In carrying out my invention I employ a cylindrical body 5 of suitable size and built 35 up from sheet metal in the usual way, provided with lugs 6 by which it may be suitably supported. The upper part of the body 7 is crowned and mounted upon the crown is a closed dome 8 which may have an outlet 40 9 for excess vapor, as indicated in broken lines, if such outlet is necessary. The bottom 10 is concave, leading to a mud discharge pipe 11. Supported upon the bottom by legs 12 is a drum 13 smaller in diameter than the diameter of the casing and 45 extending through this drum and coupled with the top and bottom thereof, are a series of tubes 14. As clearly shown in Figure 3 of the drawings, these tubes are arranged in a special way. A number of the pipes are 50 arranged equidistant from each other in the form of a square at the centre, the pipes on each side of the square forming the arms

of a cross being separated from each other equidistantly or in rows corresponding to 55 the central tubes but the pipes at the ends of the arms are arranged in transverse rows closer together than the longitudinal rows, then in the corners formed by the arms of the cross are placed pipes in rows in line 60 with the pipes of the arms of the cross. To illustrate, the distance between the pipes 15 and 16 will be one and one-half inches while the distance between the pipes 15 and 17 will be one inch. In other words, the pipes 65 around the central part of the drum and extending toward each side will be spaced an inch and one-half in one direction and one inch in the other direction. This permits 70 of free circulation of steam around the pipes and permits the steam to freely circulate among the pipes around the outer circumference of the drum. Opening into the top of the drum is a vapor return pipe 18 provided with a flaring funnel mouth 19 and in 75 the drum below the said pipe 18 is a baffle plate 20. Entering one side of the body is an inlet steam pipe 21 which is formed with branches 22 and 23 which enter the pipe 18 near its lower end. Juices are admitted 80 to the body through an inlet pipe 24 provided with a valve 25 and may be withdrawn from the body through an outlet pipe 26 provided with a valve 27. Connected with the body is the usual pressure gage 28 and 85 thermometer 29. The case is also provided with sight openings 30 and 31 through which the contents of the body may be observed. In the opening from the bottom of the drum is a condensed steam discharge 90 pipe 32. Juices to be condensed are run into the body until the drum is covered. Steam is then admitted under the desired pressure and this steam enters the pipe 18 and being directed downward creates a suction in the 95 top of the pipe 18 so as to draw the vapors arising from the juices downward into the drum. The steam heats the drum and the condensed steam is discharged through the pipe 32. As the juice becomes heated it circulates automatically up through the tubes 14 and downward around the drum and as these tubes are arranged as described, the steam reaches them all with practically the uniform degree of heat so that the action on 100 the juice is uniform throughout the drum 105

and without the aid of pumps or other mechanical power to maintain proper circulation.

I claim:

- 5 A concentrator comprising a closed evaporating chamber and a heating drum, the heating drum comprising a steam space, a vertical tube wholly within the closed chamber opening at its upper end into the upper
- 10 part of the chamber and at its lower end into the steam space and means to discharge

steam downwardly through said tube, whereby vapors from the upper part of the chamber are aspirated into the steam space.

In testimony whereof, I have signed this 15 specification in the presence of two subscribing witnesses.

OSCAR M. NELSON.
